(57) CLAIM

The ornamental design for the beverage capsule tray, as shown and described.

DESCRIPTION

FIG. 1 is a perspective view of the beverage capsule tray according to an embodiment of the present invention;

FIG. 2 is a bottom perspective view thereof;

FIG. 3 is a first side view thereof;

FIG. 4 is a second side view thereof;

FIG. 5 is a first end view thereof;

FIG. 6 is a second end view thereof;

FIG. 7 is a top plan view thereof; and,

FIG. 8 is a bottom plan view thereof.

The broken lines in the drawings illustrate the portions of the design that form no part of the claim.
